[57] CLAIM

The ornamental design for a package bow, as shown and described.

DESCRIPTION

FIG. 1 is a front elevational view of a package bow, showing my new design;

FIG. 2 is a right side elevational view;

FIG. 3 is a left side elevational view;

FIG. 4 is a rear elevational view;

FIG. 5 is a bottom plan view; and

FIG. 6 is a top plan view.

The broken line showing of an aperture in FIGS. 1 and 4 is for illustrative purposes only and forms no part of the claimed design.
